UNITED STATES PATENT OFFICE.

JAMES PHILO CALDWELL, OF WINNSBOROUGH, SOUTH CAROLINA.

COTTON-SEED PLANTER.

SPECIFICATION forming part of Letters Patent No. 643,942, dated February 20, 1900.

Application filed November 10, 1899. Serial No. 736,454. (No model.)

To all whom it may concern:

Be it known that I, JAMES PHILO CALDWELL, a citizen of the United States, residing at Winnsborough, in the county of Fairfield 5 and State of South Carolina, have invented a new and Improved Cotton-Seed Planter, of which the following is a full, clear, and exact description.

The invention relates to that class of machines employed for planting cotton-seed at regular distances apart and in uniform quantities, so as to avoid the necessity of chopping out the rows of cotton-plants after the plant has grown.

One object of the invention is to improve upon the construction of the machine for which Letters Patent were granted to me July 19, 1898, No. 607,502, and to so construct the machine that the seed will be better agitated 20 in the hopper and more positively fed to the seed-drop wheel.

It is also an object of the invention to construct the seed-drop wheel of metal, providing it with integral pockets and an improved 25 means for locking pistons in the pockets, so that any desired number of pockets may be closed for any length of time.

Another object of the invention is to improve the means for regulating the drop of 30 the pistons, and consequently the depth of the pockets, and to provide a single drive-belt for the stirrers or agitators and the seed-drop wheel.

The invention consists in the novel construction and combination of the several 35 parts, as will be hereinafter fully set forth, and pointed out in the claims.

Reference is to be had to the accompanying drawings, forming a part of this specification, 40 in which similar characters of reference indicate corresponding parts in all the figures.

Figure 1 is a side elevation of the improved planter. Fig. 2 is a transverse section through the hopper of the planter, the frame, and the 45 seed-drop wheel. Fig. 3 is a longitudinal section taken practically on the line 3 3 of Fig. 2. Fig. 4 is a section through the seed-drop wheel, taken on the line 4 4 of Fig. 2; and Fig. 5 is a side view of a part of the seed-drop 50 wheel, portions being broken away, illustrating the manner in which the piston belonging to a pocket may be locked against movement.

A represents the hopper of the planter, which is secured in any approved manner to a horizontal frame B, constructed, preferably, 55 of parallel beams placed a suitable distance apart and connected at the front by a clevis 10. A cover-board 11 is attached by arms 12 to the rear portion of the frame through the medium of bolts 13, so that this cover-board 60 may be removed from the machine whenever desired. A standard 14 is located at the front of the frame, slightly at the rear of the clevis, and this standard carries a furrow-opener 15 of any approved form, while between the hopper A and the standard 14 a supporting-wheel 16 is located in the frame, the shaft of 65 which is journaled in suitable bearings 17, secured to the beams of the frame, as illustrated in Fig. 1, and one end 18 of the shaft 70 of the supporting-wheel 16 carries a sprocket-wheel 19, as is also shown in Fig. 1. The usual handles 20 are secured to the hopper, (one at each side,) by means of which the machine is guided, the handles being attached 75 to the hopper by bolts 20^a or their equivalents.

The front and rear portions 21 of the hopper, as illustrated in Fig. 3, incline downwardly in direction of the center of the hopper, and the bottom 22 of the hopper is in the 80 form of a plate having its upper face convexed and its under face concaved and extending from the front to the rear of the hopper, being attached to these parts by suitable flanges 23, and the bottom 22 of the hopper 85 is provided with a longitudinal slot 24, as illustrated in Fig. 2. A shaft 25 is journaled transversely in the upper portion of the hopper A, and this shaft carries agitators or stirrers C. (Shown best in Figs. 2 and 3.) Each 90 agitator or stirrer consists of a sleeve 26, secured to the shaft 25, and arms 27, radiating from the sleeve, the arms of the two stirrers or agitators being curved at their outer extremities in direction of each other and the 95 arms of one stirrer intervening the arms of the opposing stirrer. The arms 27 of the stirrers are of such length that when they are in their vertical lower position their curved ends will be in close proximity to the bottom 22 of 100 the hopper—one at each side of the slot 24 therein. The shaft 25 is journaled in suitable bearings 28, secured to the sides of the hopper, and the shaft 25 is provided at one

end with a sprocket-wheel 29. Preferably the bearings 28 are attached to or are integral with side braces 30, provided for the hopper A.

- 5 A shaft 31 is journaled at the lower central portion of the hopper, and said shaft carries a sprocket-wheel 32, and a chain belt 33 is carried over the sprocket-wheels 19, 29, and 32. As the seed-drop wheel D is secured to 10 the shaft 31, the one belt 33 serves to drive the agitators or stirrers and the seed-drop wheel, power being derived from the supporting-wheel 16.
- The seed-drop wheel consists of a disk-body 15 34, having a marginal flange 35, which is adapted to travel beneath the slot 24 in the bottom 22 of the hopper, as shown in Fig. 2, and a series of pockets 36 in the form of partial cylinders are made integral with the body 20 within the flange 35, extending from a point near the center to the body of the said flange, and the flange 35 is provided with openings 37, leading into the several pockets 36. Each pocket is provided with a longitudinal slot 25 38, extending from the point near where the pocket connects with the rim of the wheel through the opposite or inner end, and each pocket is further provided at each side of the inner end of the slot 38 with a lug 39. A piston 30 40 is located in each pocket, being adapted to operate therein through gravity, and each piston is provided with a wing-shank 41, one wing of each shank having an extension 42, that projects out through a slot 38 in the 35 pocket containing the piston. The shanks of the pistons when the pistons are in their upper positions or are in side position, as shown in Figs. 2, 3, and 4, extend out beyond the inner ends of their pockets and engage 40 with the peripheral surface of a regulating-wheel 43. This wheel is provided with peripheral teeth 44, corresponding in number to the number of pockets, and the teeth are more or less convexed, as shown in Fig. 3.
- 45 This regulating-wheel is adjustably secured to the shaft 31 by a set-screw 45 or its equivalent, as shown in Figs. 2 and 3. When the shank of a piston engages with the surface of a tooth adjacent to the rise of the next 50 tooth, the piston will occupy such position in the pocket to which it belongs as to enable the said pocket to receive a maximum quantity of seed, and when the shank of the piston is at the crown of a tooth the piston will 55 have been carried so near the periphery of the seed-wheel that the pocket will receive but a small quantity of seed. Thus it will be observed that by adjusting the regulating-wheel on the shaft 31 any necessary depth of 60 pocket may be obtained.

A shield D' is secured at its upper end to the front of the hopper A. The rear surface of this shield is concaved and extends downward to a point near the bottom of the seed-drop wheel, conforming to the contour thereof, so that as the wheel turns and the descending pockets are filled with seed the seed

cannot be discharged from the pockets until the pockets have passed the lower end of the shield, at which time the pistons through gravity will drop to the position shown at the bottom of the seed-drop wheel in Fig. 2, and the seed will be forced out from the pocket. 70

Whenever it is desired to close any one of the pockets, a cotter-pin 47 or its equivalent 75 is passed through an opening in the extension 42 of the piston belonging to the pocket, the piston at such time having its outer face flush with the periphery of the seed-drop wheel, and this opening 46 is so placed that when 80 the pin 47 has been placed as stated the pin will bear against the lug 39 on the pocket, preventing the piston from dropping downward, thus effectually closing the pocket.

Instead of increasing the number of pockets 85 36 on the planting-wheel in order to vary the distance between hills I accomplish this result by changing the diameters of the sprocket-wheels 29 and 32, which wheels are readily slipped off from their shafts and replaced by 90 others.

Having thus described my invention, I claim as new and desire to secure by Letters Patent—

1. In a planter, a rotatable seed-drop wheel 95 having pockets and seed-ejecting pistons mounted to slide outwardly therein by gravity, and a regulating-wheel normally held to rotate with the seed-drop wheel and arranged to be engaged by the inner ends of said pistons to limit the inward movement thereof, said regulating-wheel being adjustable on the seed-drop wheel to vary the innermost position of the pistons.

2. In a cotton-seed planter, a hopper having inclined sides, an opening in the bottom, a shaft journaled above the opening, and stirrers or agitators secured on the said shaft, said stirrers or agitators each comprising a sleeve and arms radiating from the sleeves, the outer extremities of which arms are curved in direction of the center of the hopper, the arms of one agitator or stirrer intervening the arms of the opposing agitator or stirrer, as described. 110

3. In a cotton-seed planter, a seed-drop wheel, comprising a body having a marginal flange, pockets formed on the body within the flange, which flange is provided with openings communicating with the pockets, pistons mounted to slide outward in the pockets by gravity, the inner ends of the pistons being arranged to extend out through the inner ends of the pockets, and a regulating-wheel normally held to rotate with the body in which 120 said pockets are formed, and having an undulating peripheral surface, with which surface the inner ends of the pistons engage, as described. 115

4. In a cotton-seed planter, the combination, 130 with a hopper having inclined sides, an arched slotted bottom, and agitators mounted to revolve in the hopper above the bottom, of a shaft journaled below the bottom of the hop-

per, a seed-drop wheel secured to the said shaft, which wheel is provided with a peripheral flange, pockets formed upon the said wheel within said flange, pistons mounted to slide outward in the pockets by gravity, a regulating-wheel normally held to rotate with the shaft carrying the seed-drop wheel, the regulating-wheel being adjustable on the shaft and provided with teeth and with convexed surfaces between the teeth, the teeth and the convexed surfaces between them being adapted for engagement by the inner ends of the pistons, and a shield located in front of the peripheral portion of the seed-drop wheel, for the purpose described.

5. In a cotton-seed planter, the combination, with a hopper having inclined sides, an arched slotted bottom, and agitators mounted to revolve in the hopper above the bottom, of a shaft journaled below the bottom of the hopper, a seed-drop wheel secured to the said shaft, which wheel is provided with a peripheral flange, pockets formed upon the said

wheel within said flange, pistons mounted to slide outward in the pockets by gravity, a 25 regulating-wheel normally held to rotate with the shaft carrying the seed-drop wheel, the regulating-wheel being adjustable on the shaft and provided with teeth and with convexed surfaces between the teeth, the teeth and the 30 convexed surfaces between them being adapted for engagement by the inner ends of the pistons, and a shield located in front of the peripheral portion of the seed-drop wheel, a drive-belt for the stirrers or agitators and the 35 seed-drop wheel, and means for locking the pistons in the pockets in a manner to close the same, as described.

In testimony whereof I have signed my name to this specification in the presence of 40 two subscribing witnesses.

JAMES PHILO CALDWELL.
